UNITED STATES PATENT OFFICE.

EUGENE W. VOGEL, OF OAK PARK, ILLINOIS, ASSIGNOR TO CHICAGO RAILWAY SIGNAL AND SUPPLY COMPANY, OF CARPENTERSVILLE, ILLINOIS, A CORPORATION OF ILLINOIS.

HIGHWAY-CROSSING SIGNAL.

Application filed March 3, 1920. Serial No. 362,974.

To all whom it may concern:

Be it known that I, EUGENE W. VOGEL, a citizen of the United States, residing at Oak Park, in the county of Cook and State of Illinois, have invented certain new and useful Improvements in Highway-Crossing Signals, of which the following is a specification.

My invention relates to a signal and particularly to a highway crossing signal used by railroads at highway crossings to indicate the approach of a train. This invention relates to that type of highway crossing signal in which the swinging or moving of a disk or banner bearing an appropriate legend across the highway indicates the approach of a train. In the early signals of this type, a disk usually having the word "Stop" and suspended by an arm from the support was set in swinging motion by a suitable mechanism actuated electrically when the train enters a certain "block." When the train passed from the "block," the signal was caused to come to rest, usually in a position above the highway. This frequently caused confusion because the legend "Stop" on the disk was always in view and there was no definite and positive indication that the way was clear and that the right of way might be safely crossed. In order to avoid possible confusion resulting from the use of a signal of this type the Interstate Commerce Commission has prescribed that in such signals the disk or banner must be concealed when the way is "clear." It then became the practice to provide a cover or "blind" behind which the swinging disk could be brought to rest, so as to be concealed from view when the way was "clear." While this complies with the regulations, nevertheless, the construction is confusing in other respects. The disk swings periodically behind the "blind" so that during its entire period of motion and while a train is on the block, it indicates alternately "stop," "clear," with each oscillation.

The object of my invention is to overcome this objection and to provide a signal of this type in which the disk is never momentarily concealed but is always in view while

a train is in the "block," and which will unmistakably indicate "danger" or "stop," but in which the disk will be concealed when the way is "clear."

An incidental object is the provision of means for accomplishing the above stated purpose by giving to the disk an additional movement beyond its usual swinging amplitude, when the way is "clear," so as to bring it behind the "blind" or cover. 55

The invention consists of the novel arrangements, constructions and devices for carrying out the above stated objects, and such other objects as will appear from the following description of my invention, illustrated in the accompanying drawings, 65 wherein:

Fig. 1 is an elevation of a typical form of highway crossing signal of the type described herein. 70

Fig. 2 is a fragmentary elevation of a similar crossing signal slightly modified.

Fig. 3 is an enlarged view, partly diagrammatic, of my invention;

Figs. 4, 5, 6 and 7 are views similar to Fig. 3, showing modified forms; and

Fig. 8 is a detail of the construction shown in Fig. 7.

Like characters of reference represent like parts in the several figures of the drawings. 80

I have shown in Figs. 1 and 2, typical forms of highway crossing signal towers to which my invention is adapted to be applied. These figures represent the aspect which the signal as a whole presents to the eye. Although my invention may be applied to any form of supporting structure as will be apparent from the following description thereof, I will describe it only in connection with the forms of supporting structures shown in Figs. 1 and 2. These structures are well known in the art and a brief description thereof will be sufficient. They comprise a support 10 having the usual box 11 with a door 12 therein and at the top a crossing bell 13, below which is a small housing 14 to contain the ringing mechanism. Near the top is a larger housing 15 having a door 16 adapted to contain the mechanism for swinging the signal or ban- 95

ner. From the housing extends the hollow arm 17 adapted to support the signal or banner over the highway and so that its movements will not be interfered with by the supporting column 10. At the end of the arm 17 is a small housing 18 within which is pivoted the arm 19 which is usually composed of a hollow one inch pipe. At the end of the arm 19 is the signal 20. This is secured to the arm 19 in any suitable manner and may comprise any suitable form of signal or warning. Usually the signal comprises a circular disk about two feet in diameter bearing an appropriate legend such as the word "Stop" and also usually carrying a red light which may be illuminated at night.

The swinging portions of the signal—that is the arm 19 and the disk 20, weigh about 50 pounds. This necessitates a special mechanism for swinging the same and also makes it advisable to use a brace 21 for supporting the end of the arm 17.

The mechanism contained in the housing 16 is adapted to swing the signal normally between the positions A and B whenever a train is approaching. The mechanism is also adapted to swing the disk higher to the position C behind the cover or "blind" 22 secured in any suitable manner to the brace 21 whenever the train has left the "block" and the way is clear. That is to say, the mechanism is adapted during the period which is usually termed "normal danger" to swing the disk between the positions A and B, so that the signal or banner is always exposed to view and unmistakably indicates "danger." When the way is clear the mechanism hereinafter described is adapted to give the disk an additional swing or impulse beyond its normal path of movement and cause it to pass behind and be concealed by the cover 22. The mechanism hereinafter described is also adapted to permit the disk to fall down to the position D and remain at rest whenever the system becomes inoperative by reason of the breaking of any of the wires of the electrical circuits or by reason of the breaking of any of the apparatus. When the signal is observed to hang at rest in the position D, it indicates that the mechanism is out of working order.

In Fig. 2 I have shown a slightly modified form of supporting structure in which the cover or "blind" 23 is supported beyond the housing 24 on the arm 25. With slight changes the mechanism adapted to swing the signal applied to the support shown in Fig. 1 is adapted to swing the signal in the support shown in Fig. 2 and to bring it to its "clear" position at the point C' behind the cover 23. The covers 22 and 23 usually bear an appropriate legend to indicate a railroad crossing.

As stated above, the housing 15 is adapted

to contain all of the mechanism for swinging the signal 20. The arm 19 bearing the signal 20 is usually pivoted in its intermediate portions at the point 26. The swinging of the signal is accomplished by suitable connecting rods 27 and 28 to be hereinafter described, which extend from the mechanism in the housing 15 through the hollow arm 18 and are pivoted at or near the end of the arm 19 within the housing 18. This is more clearly illustrated in Figs. 3 to 6 inclusive.

In order to clearly illustrate my invention I have shown the mechanism adapted to be contained in the housing 15 considerably enlarged and have shown the electric circuit for operating the same in diagrammatic form. It is of course understood that in practice the electric wires are usually enclosed in waterproof cable and are not arranged in the diagrammatic form shown in the figures of the drawing. This is a matter which, however, is well known in the railway signal art and need not be further described here.

Considering now the embodiment of my invention shown in Fig. 3, I have shown at E a diagrammatic representation of a railroad track. The track is insulated in any well-known manner at the points F and G to form a "block." The electrical circuits are so arranged that when a train enters the block E the mechanism is actuated to swing the signal 20 over the highway to indicate the approach of a train. When the train leaves the block E the mechanism is actuated to move the signal 20 behind the blind or cover 22 and indicates a clear way. Across the block E a suitable low voltage battery H is connected by wires 29 and 30. This battery normally, that is when the block E is clear, excites the magnet or relay 31 through wires 32 and 33. Accordingly this relay actuates the two-bladed switch shown conventionally at 34 and 35. When the relay is excited it closes the circuit at the point 36 and opens that at the point 37.

When a train approaches the crossing K, as soon as it enters the block E the track circuit maintained by the battery H is short-circuited. This de-energizes the relay 31 causing the switch 34 to open the circuit at 36 and the switch 35 to close that at the point 37. The closing of the switch 35 causes the establishment of several circuits. The first circuit is that which rings the crossing bell shown conventionally at 40. As shown in Fig. 1 and Fig. 2 this crossing bell is usually located at the top of the support 10. This circuit is traced as follows: from the point 37 through the wires 38 and 39 the bell 40, wire 41, the battery L, the wires 42, 43, and 44, and the switch 35, and back to the point 37. The second circuit is that which actuates the motor M to swing the signal 20.

Before tracing the second or motor circuit the swinging mechanism will be described. As previously stated the signal 20 is oscillated by means of the two connecting rods 27 and 28 passing through the hollow arm 17 and shown broken in Fig. 3 for convenience in illustration. The connecting rod 28 connected at the opposite end of the arm 19 gives to the signal 20 its normal oscillation, that is from the position A to the position B. The connecting rod 27 connected at a point closer to the pivot 26 gives the signal 20 its extreme motion or oscillation capable of bringing it to the position C behind the cover 22. I have shown electrically controlled mechanism 45 and 46 which I will describe later for rendering one connecting rod inoperative to oscillate the signal 20 while the other connecting rod is operative for swinging the signal 20. That is to say, when the connecting rod 28 is operative to oscillate the signal through its normal path of movement, the connecting rod 27 is inoperative and vice versa.

To one end of the shaft of the motor is secured a small spur gear 47 meshing with a larger gear 48 which carries a smaller gear 49, the latter meshing with a large gear 50. A connecting rod 51 is pivoted eccentrically at 52 to the gear 48 and serves through the rod 53 and mechanism 45 to oscillate the connecting rod 28. The connecting rod 54 pivoted to the large gear 50 eccentrically at a point 55 serves to oscillate the arm 27 through the rod 56 and the mechanism 46. The rod 53 reciprocates in suitable guides or between rollers 57. It is provided near the end with a V-shaped notch 58 into which the V-shaped projection 59 on the connecting rod 28 is adapted to fit. The notch 58 and the projection 59 are so shaped that the projection 59 will slide out of engagement with the notch 58 unless retained there by suitable mechanism shown at 45. The mechanism 45 comprises a magnet 60 which actuates an armature 61 pivoted at 62 and having a roller 63 thereon which is capable of pressing on the upper side of the rod 28 and exerting downward pressure thereon to cause the projection 59 to enter and remain in the notch 58 when they register with each other.

The mechanism 46 corresponds exactly with the mechanism 45 and need not be described. The electrical circuits are so arranged that when the magnet 60 is energized, the magnet 64 is de-energized so as to permit the projection 65 to pass out of the recess 66 and thus sever the mechanical connection of the connecting rod 27 with the rod 56.

As long as the crossing K is clear, that is as long as there is no train in the block K, the magnet 64 remains energized through the circuit traced as follows: from the magnet

64 through the wire 67, the point 36, switch 34, wires 68, 43 and 42, the battery L, wires 69, 70 and 71, back to the magnet 64. The magnet attracts its armature 72 and causes the roller 73 to press on the connecting rod 70 27 and keep the projection 65 in the recess 66.

The signal 20 is maintained in its extreme position behind the cover 22 when the crossing is clear by the engagement of the spring 75 member 74 with the stop 75 which is attached to and forms a part of the housing 15.

When the circuit through the magnet 64 is broken by the entry of a train upon the block, the armature 72 falls of its own weight and releases the projection 65 from forcible engagement with the recess 66. The weight of the signal 20 which, as previously stated, is about 50 pounds, aids to force the projection 65 out of the notch 66. This raises the connecting rod 27 a short distance above the rod 56 and causes the spring member 74 to clear the stop 75. The signal 20 is then free to swing downwardly of its own weight. When it has moved a very short distance the insulated stop 76 permits the switch 77, which is held open as long as the signal is held in its position C, to close on the point or contact 78. The electrical circuit through the motor is now complete and the motor is caused to revolve and reciprocate the connecting rods 51 and 54. The motor circuit may be traced as follows: from the battery L through the wires 69 and 79, the point 78, the switch 77, and the wire 80 100 to the motor M, through the motor and the wires 81 and 42 back to the battery L.

When the relay 31 is de-energized by the approach of a train a third circuit through the magnet 60 is established. This 105 is traced as follows: from the point 37 through the wires 38 and 82, through the magnet 60, the wires 83, 70, 69, the battery L, the wires 42, 43, and 44, and the switch 35 back to the point 37. The excitation of the magnet 60 causes it to attract its armature 61 and the roller 63 to press downwardly on the connecting rod 28. When the motor M through the gear 48 has reciprocated the rod 53 to a point where 115 the recess 58 is directly beneath the projection 59, the same is caused to fall therein and remain there by the pressure of the roller 63. This completes the mechanical connection between the motor M and the connecting rod 28. The pivot 52 is positioned on the gear 48 so as give the same a crank arm capable of oscillating or swinging the signal 20 between the positions A and B. During the reciprocation of the connecting rod 51, the connecting rod 54 also reciprocates though much more slowly due to the extreme gear reduction from the motor to the gear 50, but owing to the fact 125 that the magnet 64 is deenergized the me-

130

chanical connection between the connecting rod 54 and the connecting rod 27 is broken. Accordingly, though both the connecting rods 27 and 54 reciprocate they are not mechanically connected to each other.

When the train leaves the block E the relay 31 is again energized by the battery H and picks up the armature controlling the switches 34 and 35. This breaks the circuit at the point 37 and closes that at the point 36. The breaking of the circuit at the point 37 also deenergizes the magnet 60 and severs the mechanical connection between the connecting rod 28 and the connecting rod 51. Simultaneously, however, with the de-energization of the magnet 60, the magnet 64 is energized so that when the recess 66 passes beneath the projection 65 the same is forced therein by the pressure of the roller 73 on the connecting rod 27. The signal 20 accordingly continues to swing but with a swing of greater amplitude. The increase in swing of the signal 20 is accomplished by connecting the connecting rod 27 closer to the pivot 26 and also by pivoting the connecting rod 54 at a point farther removed from the center of the gear 50. When the connecting rod 54 approaches its far dead center the insulated stop 76 breaks the circuit through the switch 77 and the point 78. At the same time the spring member 74 snaps over the stop 75 and holds the signal 20 in position C behind the cover 22. The opening at the switch 77 breaks the motor circuit and the motor promptly stops. The motors used in signals of this character are usually provided with a well-known type of magnetic brake so that the brake is applied as soon as the circuit through the motor is open. This is for the purpose of suddenly stopping the revolution of the motor.

Considerably greater power is required to raise the signal 20 to the position C than that required to oscillate it from the position A to the position B, this being largely because of the relatively great weight of the signal itself. The increase in power is accomplished by the gear reduction through the gears 49 and 50. It will be evident that though the connecting rod 54 reciprocates much more slowly, it possesses considerably greater power and accordingly is capable of raising the signal 20 to the position C behind the cover 22.

Considering now the modifications shown in Fig. 4, the mechanical features of this modification are so similar to those of Fig. 3 that they need be only briefly described.

The chief point of difference is the use of a separate magnet for actuating the latch which maintains the signal in its extreme position.

As in the previous modification, the entry of a train on the block E de-energizes

the magnets 31 and 64 and energizes the magnet 60. When the train leaves the block the relay 31 and the magnet 64 are energized and the magnet 60 de-energized. The additional magnet referred to is the magnet 84. This magnet remains energized while the block is clear and is de-energized by the approach of a train when it enters the block E. The circuit through the magnet 84 is traced as follows: from the point 36 through the wires 85, 86 and 87, the battery L, the wires 88, 89 and 90, through the magnet 84, the wire 91, the switch 34, back to the point 36. The magnet 84 attracts the armature 92 to which the switch 93 is attached and closes a circuit at the point 94 through the magnet 64 which is traced as follows: from the point 94 through the wire 95, the magnet 64, the wires 96, 87, the battery L, the wires 88, 89 and 97, 85 the switch 93, back to the point 94.

When a train enters the block, the circuit through the switch 34 is broken at the point 36 and the switch 35 is caused to contact with the point 37. The breaking of the switch at the point 36 de-energizes the magnet 84 and causes the armature 92 to fall and closes the switch 93 with the point 98. The closing of the latter switch completes the circuit through the magnet 60 which is traced as follows: from the point 98 through the wire 99, the magnet 60, the wires 96 and 87, the battery L, the wires 88, 89, 97, the switch 93 back to the point 98.

The falling of the armature 92 by its own weight disengages the opposite end 100 thereof from the stop 101 on the connecting rod 28. This causes the signal 20 to move downwardly and moves the stop 101 away from the switch 102, thus closing the motor circuit at the point 103. The motor circuit is traced as follows: from the point 103 through the wires 89 and 88, the battery L, the motor M, the wire 104, the switch 102 back to the point 103.

The excitation of the magnet 60 completes the mechanical connection between the connecting rod 28 and the connecting rod 51 and causes the motor to swing the signal 20 between the positions A and B. This swinging is continued until the train leaves the block, whereupon the relay 31 is energized closing the circuit at the point 36 and energizing the magnet 84. This in turn closes the switch 93 at the point 94 and energizes the magnet 64 and de-energizes the magnet 60. This severs the mechanical connection between the connecting rods 28 and 51 and completes the mechanical connection between the connecting rod 54 and the connecting rod 27. As in the construction shown in Fig. 3 the signal is now given an increased swing which eventually brings it to the position C behind the cover 22, at which time the motor circuit is broken by 130

the opening of the switch 102 by the stop 101. The signal is held in position C by the engagement of the stop 101 with the member 100 of the armature.

5 In other respects the operation of the modification shown in Fig. 4 is the same as that in Fig. 3.

In Fig. 5 I show a construction somewhat similar to that shown in Fig. 4 differing mainly in the use of a different form of magnetic clutch. The electrical circuits are the same as those shown in Fig. 4. In place of the clutch mechanisms 45 and 46 of Figs. 3 and 4, I make use of a different 15 form of clutch mechanism shown at 105 and 106. These clutch mechanisms which are duplicate serve to establish a mechanical connection in one case between the connecting rod 51 and the main connecting rod 107 which operates through the hollow arm 17 to swing the signal through its normal path between positions A and B and in the other case between the connecting rod 54 and the main connecting rod 107 for giving to the 20 signal the additional swing to bring it behind the cover 22. The clutch mechanism 106 consists of two links 108 and 109, the former being pivoted to the connecting rod 51 and the latter to the connecting rod 111. They are pivoted to each other at the point 25 110. To one of the links, in this case link 109, is secured a magnet 112. An armature 113 is secured to the link 108 at a point which passes beneath the magnet 112. The 30 construction is such that when the magnet 112 is excited it attracts the armature 113 and prevents it from swinging past the face of the magnet, the contacting surfaces being roughened or notched, as illustrated, to prevent slipping. This, in effect, makes the 35 links 108 and 109 a solid member and serves to mechanically connect the connecting rod 51 with the connecting rod 111 which in turn is pivoted at the point 114 to the main connecting rod 107. When the magnet 112 is not energized the armature 113 on the 40 link 108 is free to swing past the face of the magnet and thus the connecting rod 51 transmits no motion to the connecting rod 111.

The construction of the clutch mechanism 105 is exactly similar to that of 106 and need not be described. The electrical connections are arranged so that when the magnet 115 is energized the magnet 112 is de-energized. Accordingly it will be seen that the same action as with the clutch mechanisms 45 and 46 of Fig. 3 is secured.

45 The connecting rod 107 is hinged at the point 116. The extreme end thereof runs between suitable guides or rollers 117.

As is the case with the construction shown in Fig. 4, when the block is clear the relay 31 and the magnets 115 and 118 are energized. When the block is occupied these

magnets are de-energized and the magnet 112 is energized and the circuit through the motor is closed by the switch 119. The circuit through the magnet 112 is completed when the armature 22 falls on the de-energization of the magnet 118 permitting the switch 121 to close the circuit through the magnet 112 at the point 120. The falling of the armature 122 also disengages the latch 123 from the rear of the stop 124 and permits the signal to swing downwardly, thus, as previously stated, permitting the switch 119 to close and complete the circuit through the motor.

50 In order that the gear 50 may be capable of giving to the signal 20 a swing greater than that given to it by the gear 48 the pin 55 is set sufficiently far from the center of the gear so as to bring the signal 20 to position C when the gear approaches its dead center.

55 It is believed that the operation of the modification shown in Fig. 5 will be sufficiently clear in view of the description of the modification shown in Fig. 3, and accordingly no further description is necessary.

Coming now to a description of the modification shown in Fig. 6. The mechanism in this modification is arranged to hold the 60 signal 20 in the position C' so as to adapt it for use in connection with the signal shown in Fig. 2. It is apparent, however, that with very slight alteration the mechanism could be changed to hold the signal in the 65 position C as in the other modifications. And in like manner the other modifications could be changed with slight alteration to hold the signal in the position C'.

The modification shown in Fig. 6 differs 70 chiefly from the other modifications in the type of clutch mechanism used. The signal is oscillated both for a normal and extreme oscillation by two beveled gears, 125 and 126, which reciprocate connecting rods 127 and 128 respectively. The rod 127 is connected to the arm 19 at the point 129 by means of a loose connection hereinafter described. This rod gives the signal 20 its normal swing 75 between the positions A and B. The extreme oscillation is given to the signal by means of the rod 128 connected at the point 130 to the arm 19. The gear 126 is preferably made larger than the gear 125 so as to possess greater power in raising the signal 80 to the position C'. The gears 125 and 126 are driven by the double-beveled gear 131 splined to the shaft 132 of the motor. The gears are so disposed that by shifting gear 131 along the shaft it is capable of meshing 85 either with the gear 125 or the gear 126. I have shown a magnetic gear shift which consists of the shifting arm 133 having a forked end 134 which extends around the gear 131 and is capable of shifting it and pivoted at 90

the point 135. At 136 I have shown a double solenoid magnet having an armature attached to the opposite end 137 of the arm 133. The solenoid consists of two magnets 138, and 139, disposed on opposite sides of the armature and is capable of oscillating the arm 133 from one side to another so as to shift the gear from mesh with one gear to the other.

10 When a train approaches the crossing K the magnet 31 is de-energized causing the switch 35 to close on the point 37. This energizes the magnet 139 and causes the gear 131 to mesh with the driven gear 125, causing the signal to oscillate between the positions A and B. The opening of the switch 34 de-energizes the magnet 140 permitting the armature 141 pivoted at 142 to fall and release the latch 143 from engagement with the extension 144 of the arm 19. This permits the signal to fall and closes the switch 145 on points 146. This closes the motor circuit and causes the motor to revolve.

25 When the train leaves the block the magnet 31 is again energized closing the switch 34 and energizing the magnet 138. This causes the gear to be shifted to mesh with the larger driven gear 126 and the signal is caused to oscillate with a greater swing. 30 When the signal reaches the position C' the insulated end of the projection or extension 144 opens the switch 145 and the motor circuit causing the motor to stop. At the same time the latch 143 engages with the extension 144 and holds the signal in the position C'.

35 By reason of the fact that the gears 125 and 126 and the faces of the gear 131 are beveled, they will be thrown out of mesh by the weight of the signal 20 in case, for any reason, the electrical circuits are broken. This will permit the signal to hang vertically and indicate that the circuit is inoperative.

45 In view of the fact that the connecting rods 127 and 128 have strokes of different lengths in order to oscillate the signal through paths of different amplitude, it is necessary to provide a loose connection between the connecting rod having the shorter stroke and the arm 19. This may be accomplished as shown by providing a fork at the end of the rod 127 within which is arranged a small cross head 147 pivoted to the arm 19 at the point 129. Between the cross head 147 and the bottom of the fork a small compression spring 148 is interposed. This spring normally holds the cross head 147 at the extreme end 149 of the fork. When, 50 however, the connecting rod 128 oscillates the signal 20 the spring 148 is capable of being compressed to compensate for the difference in length of the respective strokes of the rods 127 and 128. This form of connection is illustrative only and it is evident that

any form of loose connection may be satisfactorily used. The spring 148 serves the additional function of giving to the arm 19 a small impulse when the latch 143 is lifted. Ordinarily this is sufficient to close the switch 145. This action, however, is not necessary, inasmuch as the weight of the signal is sufficient to cause it to swing downwardly and close the switch 145.

55 In Figs. 7 and 8 I have illustrated an embodiment of my invention in which the "blind" or cover for concealing the moving banner or disk is moved out of the path of motion of the disk when a train enters the block, and is thereafter returned to its normal position concealing the disk when the train leaves the block.

60 The motor M when set in motion is adapted to drive the gear 150 through the pinion 151 on the shaft of the motor. The arm 152 connected to the gear 150 at 153 (Fig. 8) and the banner arm 154 at the point 155, is adapted to swing the banner or disk 156. The banner 156 is swung from the pivot 157, and is normally concealed when no train is on the block, behind the "blind" or cover 158. The banner bears a suitable legend, as for instance the word "Stop," and the blind some like legend indicating a railroad crossing.

65 The "blind" 158 is supported by the movable arm 159 pivoted at 160 and having a curved rack 161 thereon having as its center of curvature the pivot 160. The rack 161 meshes with the pinion 162, which is connected with the larger gear 163, which in turn meshes with the gear 166. An electromagnetic clutch, shown somewhat diagrammatically in Fig. 8, comprising the solenoid 165, the sliding gear 166, and toggle arms 167 is adapted to establish a mechanical connection between the pinion 166 and the gears 150 by means of the beveled dogs 168 on the pinion and the corresponding dogs 169 on the gear 150. Upon the excitation of the solenoid 165 the toggle arms 167 are drawn down by means of the rod 170 and the gear 166 is moved by means of the sliding shaft 171 into engagement with the gear 150. The function of this construction will be later described.

70 A magnetically controlled latch 172 having a projection 173 with a beveled face adapted to engage the projection 174 with a corresponding beveled face on the rack 161 normally holds the cover 158 over the disk or banner 156. When the magnet 175 is de-energized, the weight of the cover 158 is adapted to force the latch 172 out of engagement with the projection 174 and to permit the cover to swing down to the position shown in dotted lines at 176, and to expose the disk 156.

75 The rack 161 carries a projection 177 which is adapted to engage the arm 178 when

the cover 158 is in its highest position. The arm 178 is connected to the electric switch arm 179, and in the position just described, holds the switch arm out of contact with the 5 electric contact 180 against the tension of the spring 181.

When a train enters the block, the magnet 31 is de-energized, thus permitting the switch arm 182 to close with its contact 183, 10 and the switch 184 to break contact with the point 185. The opening of the switch 184 de-energizes the magnet 175 and the solenoid 165, thus releasing the latch 172 and disconnecting the gears 166 and 150. The 15 cover 158 then moves down to its position 176 through its own weight, a suitable stop preventing further downward movement, thus causing the gears 163 and 166 to revolve. The movement of the projection 177 away from the arm 178 permits the closing 20 of the switch 179 and the establishment of a circuit through the motor. This circuit is traced as follows: from the contact 180 through wire 186, motor M, wires 187, 188, 25 battery L, wire 189 and the switch arm 179 to which the wire 189 is connected. The establishment of this circuit causes the banner 156 to swing back and forth. The closing 30 of the switch arm 182 on the contact 183 closes the circuit to the bell 40 by means of the wires 190, 191 and 192. When the train leaves the block, the magnet 31 is again energized, thus opening the switch 182 and closing the switch 184 on the contact 185. 35 This establishes a circuit through the magnet 175 and the solenoid 165 as follows: from the contact 185 through the wire 193, magnet 175, wire 194, solenoid 165, wires 195, 188, the battery L, the wires 192, 196, 40 and the switch arm 184. This causes the closing of the clutch shown in Fig. 8, and mechanically connects the gear 166 with the gear 150 and causes the gear 162 to rotate in a clockwise direction, thus raising the 45 cover 158 to its normal position over the banner 176. When the cover 158 is in its highest position, the latch 173 snaps over the projection 174 and the projection 177 opens the switch 179 and breaks the circuit 50 through the motor M.

In the event that the signal should become inoperative by reason of the breaking of any of the electric wires, or because of the weakening of the batteries L or H, the magnet 175 and the solenoid 165 would become de-energized and permit the banner 156 to be exposed, thus indicating that the signal was 55 out of order.

While I have shown the arm 159 as being 60 weighted by the cover plate 158 so as to move downwardly when released by the latch 173 as above described, it will be understood that I do not wish to be restricted to this particular form, except as hereinafter specifically claimed. If the arm were arranged to

have some other suitable movement for clearing the plate 156, the operating mechanism would of course be modified accordingly.

The operating mechanism, as shown at the left hand of Figure 7, is adapted to be contained within the box 15 (Fig. 1). The arm 152 is adapted to pass through the supporting arm 17 (Fig. 1).

It is evident that my invention may be practiced with many other forms of mechanism than here described. Moreover, the invention is not limited to the particular form of mechanism used for actuating the signal or other moving parts.

I claim:

1. A highway crossing signal comprising a tower, a swinging arm having a disk pivoted to said tower and adapted to be positioned over a highway, a concealing cover behind which said disk is held concealed, electrically controlled means for holding said disk in concealed position and for releasing said disk to permit it to swing, an electric motor operating a connecting rod attached to said arm to swing said arm and disk in a path clear of said cover, and a second connecting rod attached to said arm and operated by said motor for giving to said disk a greater swing to cause it to pass behind said cover and be held there by said holding means.

2. A highway crossing signal comprising a tower, a swinging arm having a disk pivoted to said tower and adapted to be positioned over a highway, a concealing cover behind which said disk is held concealed, electrically controlled means for holding said disk in concealed position and for releasing said disk to permit it to swing, an electric motor operating a connecting rod attached to said arm to swing said arm and disk in a path clear of said cover, a second connecting rod attached to said arm and operated by said motor for giving to said disk a greater swing to cause it to pass behind said cover and be held there by said holding means, and means for rendering one connecting rod inoperative while the other is swinging the disk.

3. In a device of the type described, a swinging signal, a motor, a rod reciprocated by said motor and connected to said signal for normally swinging it through a certain arc, reduction gearing on said motor, and another rod reciprocated by said reduction gearing and connected to said signal for swinging said signal through an arc larger than said first-mentioned arc.

4. In a device of the type described, a swinging signal, a motor, a rod reciprocated by said motor and connected to said signal for normally swinging it through a certain arc, reduction gearing on said motor, and another rod reciprocated by said reduction gearing and connected to said signal for ap-

plying greater power to said signal to raise it to a position higher than it reaches during its normal swing.

5. In a device of the type described, a swinging signal, a motor, a rod reciprocated by said motor for normally swinging said signal through a certain arc, a magnetic clutch for connecting said rod to said signal, a second rod reciprocated by said motor for 10 swinging said signal through an arc greater than said normal arc, a magnetic clutch for connecting said rod to said signal, an electrical circuit for energizing said first magnetic clutch for mechanically connecting said 15 rod to said signal, a second electrical circuit for actuating said second magnetic clutch to mechanically connect said second rod to said signal, and electrically controlled means for controlling said circuits so as to cause 20 said first clutch to engage when the second named clutch is disengaged and vice versa.

6. A railway crossing signal comprising a movably mounted signal, a concealing cover, means for moving said signal positively back, 25 and forth in the clear with respect to the cover, other means for moving said signal positively beyond the limit of its movement by said first named moving means and into position behind said cover, and electrically 30 operated means for controlling the operation of said several signal moving means for causing them to act alternatively.

7. A railway crossing signal comprising a movably mounted signal, a concealing cover, 35 a motor, means actuated by said motor for moving said signal positively back and forth in the clear with respect to said cover, other means actuated by said motor alternatively for moving said signal positively beyond 40 the limit of its movement by said first named moving means and into position behind said cover, means actuated by the movement of said signal into concealed position for stopping the operation of said motor and actuated by the movement of the signal out of 45 concealed position for starting the motor into operation, and electrically operated means for controlling the operative connections between said motor and said several 50 signal moving means.

8. A railway crossing signal comprising a pivotally mounted arm, a signal carried by said arm, a connecting rod pivotally connected with said arm, a second connecting 55 rod pivotally connected with said arm at a shorter distance from the axis of said arm than said first named arm, power means alternatively connected with said rods for reciprocating them, means controlled by the 60 movement of the second connecting rod to and from the limit of its motion for stopping and starting the operation of said power means, and controlling means for regulating the alternative operation of said 65 connecting means.

9. A signal of the class described, comprising a tower having a supporting arm extending therefrom, an oscillating banner supported from the extremity of said supporting arm, operating means located within 70 said tower for normally positively oscillating said banner within a certain path, means for concealing said banner located beyond its normal path, and other means located in said tower and connected with 75 said banner for moving said banner so as to be concealed by said concealing means.

10. A signal of the class described, comprising a tower having a supporting arm extending therefrom, an oscillating banner supported from the extremity of said arm, operating means located within said tower and connected with said banner for normally positively oscillating said banner within a defined amplitude, a cover for concealing said banner located beyond the normal amplitude of oscillation, and means operated by the operating means in said tower for giving to said banner an impulse of greater amplitude than its normal amplitude 90 to cause it to pass behind and be concealed by said cover.

11. A highway crossing signal comprising a tower, an arm extending from said tower, a swinging signal disk supported from the extremity of said arm, a concealing cover behind which said disk is held concealed, means for holding said disk in concealed position and for releasing the same to permit it to swing, and mechanism supported 100 by said tower and remote from said swinging disk and being adapted to positively swing said disk in a path clear of said cover, said operating mechanism adapted to give said disk a greater swing to cause it to pass behind said cover and engage the holding means.

12. A highway crossing signal comprising an oscillating banner, means for positively swinging said banner through a definite arc during "danger" periods, a cover for concealing said banner located beyond said arc of oscillation, and means for positively swinging said banner behind said cover at the end of a "danger" period.

13. A highway crossing signal comprising a tower, a banner arranged to swing from said tower, a connecting rod adapted to be connected with said banner, an electric motor for reciprocating said connecting rod for normally swinging said banner, a second connecting rod for swinging said banner through an arc greater than the normal swing, and means for operatively connecting said banner with said first-named connecting rod during "danger" periods and for connecting said second named connecting rod with said banner at the ends of "danger" periods.

14. In a highway crossing signal, the com- 130

bination of a tower, a banner supported to swing from said tower, a rod connected with said banner and adapted to reciprocate to swing said banner, electrically controlled mechanism for reciprocating said rod to swing said banner through a given path, concealing means located beyond said path, electrically controlled means adapted to be actuated to increase the swing of said banner so as to move it into position where it is concealed by said concealing means, and electrically controlled holding means for holding said banner in concealed position. 10

EUGENE W. VOGEL.
